UNITED STATES PATENT OFFICE

PATRICK H. ROBINSON, OF WATERBURY, CONNECTICUT, ASSIGNOR TO HAMILTON BEACH MANUFACTURING COMPANY, OF RACINE, WISCONSIN, A CORPORATION OF WISCONSIN

VACUUM CLEANER

Application filed October 19, 1929. Serial No. 400,806.

This invention relates to improvements in vacuum cleaners, and more particularly to a combination fan shaft and pulley for driving the belt connecting the drive shaft and brush shaft of a vacuum cleaner.

The invention is particularly adapted for use where the power shaft is at right angles to the driven shaft.

Heretofore, in vacuum cleaners it has been found very difficult to arrange a fan shaft so that the belt, connecting it with the brush pulley, will stay in position, especially when the motor is stopped and started, the natural inclination being for the belt to run off the shaft.

One of the objects of the present invention is to overcome the above mentioned difficulty by providing a combination shaft and pulley so constructed and arranged relative to the brush pulley that if the belt runs off of the pulley portion, the shaft portion there adjacent will direct it back to the pulley.

Another object is to provide a combination shaft and pulley which is devoid of notches and flanges, such as have heretofore been used to retain the belt on the shaft; these notched or flanged constructions being objectionable because of the friction on the belt when in contact therewith and undue wearing of the belt in use.

The construction of the combination shaft and pulley of the present invention is such that when the belt is subjected to overload, as is the case when the free rotation of the brush is interfered with for any reason, the undue tension is relieved by the tendency of the belt to run toward the free end of the tapered shaft, the angle of the taper and the relationship of the tapered shaft to the brush shaft being such that the belt will stop when it gets to the small end of the tapered shaft. As soon as excess load has been relieved and the shaft gains speed, the belt will be re-engaged frictionally, and will run up on the tapered portion 14 until it climbs onto the pulley 11 which is its normal operative position.

Another advantage is the fact that the pulley and shaft are self-cleaning, the automatic reciprocation of the belt longitudinal-

ly of the shaft and pulley being effective to keep them free from dust and lint.

In the accompanying drawings in which the same reference characters indicate the same parts in both of the views:

Fig. 1 is a fragmentary side elevation of a vacuum cleaner having part of the nozzle broken away to show the location of the improved shaft; and

Fig. 2 is a detail view of the shaft and pulley on a larger scale.

Referring now more particularly to the drawings, 5 indicates a vacuum cleaner having the usual nozzle 6 in the lower portion of which is mounted a rotatable brush shaft 7 carrying a pulley 8. Power is transmitted to the brush shaft by means of a belt 9 riding over said pulley.

A motor (not shown) positioned within the body portion of the vacuum cleaner is the source of power and connected to the motor shaft (not shown) is the improved combination shaft and pulley 10. The shaft 10 is at right angles to the brush shaft 7, a half turn being given to the belt 9 whereby the shafts 7 and 10 are connected. The belt 9 normally rides over the brush pulley 8 and the pulley 11 of the shaft 10.

The improved combination shaft and pulley 10 may be secured to the motor shaft in any suitable manner. As shown in detail in Fig. 2, it comprises a threaded inner end portion 12 for attachment to a motor shaft. A straight shank portion 13 of substantial length extends from the threaded end portion to the pulley portion 11, which is rounded, as shown. Extending outwardly from the pulley portion 11 is a tapered end portion 14. The taper is quite slight but the inclination and the location relative to the brush pulley are such as to insure the relieving of tension when the belt is overloaded and the return to the pulley when tension has been relieved. The curved pulley portion 11 of the shaft is located above and slightly rearwardly of the rear edge of the brush pulley 8, and the tapered end 14 of said shaft extends to a point located approximately above the forward edge of the brush pulley 8. This arrangement, as heretofore explained, permits recip-

rocation of the belt 9, longitudinally of the pulley 11 and shaft 14.

I claim:—

1. In a vacuum cleaner having a suction nozzle, a brush carrying shaft rotatably mounted in the suction nozzle parallel with the mouth of the nozzle, a drive shaft located at right angles to a plane including the axis of the brush carrying shaft and a belt extending around said brush shaft and drive shaft for driving the brush shaft, said drive shaft consisting of an elongated member having an unobstructed tapered end and a rounded pulley portion merging with the tapered end.
2. In a vacuum cleaner, in combination with a nozzle having a suction mouth, a brush shaft in said nozzle paralleling the mouth, a horizontal brush drive shaft extending at right angles to the vertical plane including the axis of said brush shaft and having an unobstructed forwardly tapered free end portion extending to a point located above the forward edge of said brush shaft, a pulley on said drive shaft merging with the inner end of said tapered portion and a belt for driving said brush shaft from said pulley, said pulley and tapered end portion of said drive shaft co-operating with the brush shaft to cause longitudinal reciprocation of said belt on said drive shaft when said belt is subjected to overloads from the brush shaft.

In testimony, that I claim the foregoing as my invention, I affix my signature, this 7th day of October, 1929.
